Primary Examiner — Michael D Dennis(74) *Attorney, Agent, or Firm* — Oliff PLC(57) **ABSTRACT**

A golf club head, when oriented in a reference position, includes: a striking face; a top portion; and a sole portion opposite the top portion. The sole portion includes a leading edge, a trailing edge, at least one sole rail generally elongate in a front-to-rear direction, and a sole contact point located on the at least one sole rail. In a virtual vertical plane extending in the front-to-rear direction and passing through the sole contact point, (i) the sole portion includes a sole length L_s measured in the front-to-rear direction from the leading edge to the trailing edge and (ii) the sole contact point is spaced rearwardly from the leading edge by a distance D_1 no greater than $0.8*L_s$.

GOLF CLUB HEAD WITH SOLE RAILS**RELATED APPLICATIONS**

This application is a continuation-in-part of U.S. patent application Ser. No. 16/502,631, filed Jul. 3, 2019. The entire contents of that prior application are incorporated by reference herein.

BACKGROUND

This disclosure relates generally to the field of golf clubs. More particularly, it relates to a golf club head with at least one sole rail.

Many factors can influence the effectiveness of a golf shot. One of the most important of these factors is the speed at which the club head strikes the golf ball. This club head speed at impact not only substantially dictates how far the golf shot will travel, but its predictability and repeatability are of utmost importance for a golfer to hit a shot at a desired distance. Another factor influencing the effectiveness of the golf shot is the trajectory at which the golf ball leaves the club face following impact. This trajectory has a substantial impact on the ball's distance of travel, ability to clear hazards, and movement once having returned to the ground surface.

SUMMARY

One of the largest influences on the speed at which the club head strikes the golf ball is the effort exerted by the golfer, i.e., how hard the golfer swings. Large influences on the trajectory of the golf ball are the loft angle of the club head itself as well as the angle at which the club head attacks the ball during the swing. But interaction between the club head and the turf can also result in an unanticipated loss of club head speed prior to impact with the golf ball, and it can also result in de-lofting, i.e., flattening, of the club head prior to impact. This may lead to the aforementioned changes in and adverse declines in predictability of shot distance and golf ball trajectory following impact. This is especially true with respect to hybrid or utility-type golf club heads, which are often employed in adverse turf conditions such as the rough, which may offer more resistance to the club head and thereby substantially reduce speed retention, and which club types are generally relied on for longer golf shots than say irons and wedges.

A golf club head has thus been sought that improves club head speed retention throughout the swing and prevents loss of this speed due to turf interaction. This goal may be achieved by one or more aspects of the present disclosure, in which the sole contour of the club head, e.g., its width and leading edge shape, may be designed for this specific purpose by way of optimization through numerous iterations.

A golf club head according to one or more aspects of the present disclosure may thus, when oriented in a reference position, comprise: a striking face; a top portion; and a sole portion opposite the top portion. The sole portion may in turn comprise a leading edge, a trailing edge, at least one sole rail generally elongate in a front-to-rear direction, and a sole contact point located on the at least one sole rail. And in a virtual vertical plane extending in the front-to-rear direction and passing through the sole contact point, the sole portion may include a sole length L_s measured in the front-to-rear direction from the leading edge to the trailing

edge, and the sole contact point may be spaced rearwardly from the leading edge by a distance D_1 no greater than $0.8*L_s$.

A golf club head in accordance with one or more aspects of the present disclosure may, when oriented in a reference position, also comprise: a striking face; a top portion; and a sole portion opposite the top portion. The sole portion may in turn comprise a leading edge, a trailing edge, a first sole rail generally elongate in a front-to-rear direction, a second sole rail generally elongate in the front-to-rear direction, and a recess formed between the first sole rail and the second sole rail. The recess may have a step-down portion defined in the front-to-rear direction.

And a golf club head in accordance with one or more aspects of the present disclosure may, when oriented in a reference position, yet further comprise: a striking face; a top portion; and a sole portion opposite the top portion. The sole portion may comprise a leading edge, a trailing edge, at least one sole rail generally elongate in a front-to-rear direction, and a sole contact point located on the at least one sole rail. And in a virtual vertical plane extending in the front-to-rear direction and passing through the sole contact point, the leading edge may include a height H_1 of no less than 5 mm; the sole may further comprise a first radius of curvature R_1 at a first location spaced rearward from the leading edge by no less than 3 mm and a second radius of curvature R_2 at a second location rearward of the first location; and R_2 may be no less than $10*R_1$.

These and other features and advantages of the golf club head according to the various aspects of the present disclosure will become more apparent upon consideration of the following description, drawings, and appended claims. The description and drawings described below are for illustrative purposes only and are not intended to limit the scope of the present invention in any manner. It is also to be understood that, for the purposes of this application, any disclosed range encompasses a disclosure of each and every sub-range thereof. For example, the range of 1-5 encompasses a disclosure of at least 1-2, 1-3, 1-4, 1-5, 2-3, 2-4, 2-5, 3-4, 3-5, and 4-5. Further, the end points of any disclosed range encompass a disclosure of those exact end points as well as of values at approximately or at about those endpoints.

BRIEF DESCRIPTION OF THE DRAWINGS

Exemplary embodiments of the present disclosure will now be described with reference to the accompanying drawings.

FIG. 1 shows a top plan view of a golf club head in accordance with one or more exemplary embodiments.

FIG. 2 shows a front side view of the golf club head of FIG. 1.

FIG. 3 shows a bottom plan view of the golf club head of FIG. 1.

FIG. 4 shows a cross-section view of the golf club head of FIG. 1.

FIG. 5 shows a partial detail of the cross-section view of the golf club head of FIG. 1.

FIG. 6 shows another cross-section view of the golf club head of FIG. 1.

FIG. 7 shows a graph with club head speeds of a golf club head in accordance with one or more exemplary embodiments and a comparative club head.

FIGS. 8A and 8B show dynamic turf movement from interaction with the comparative and exemplary golf club heads, respectively.

FIG. 9 shows a front side view of a golf club head in accordance with one or more exemplary embodiments.

FIG. 10 shows a side view of the golf club head of FIG. 9.

FIG. 11 shows a bottom plan view of the golf club head of FIG. 9.

FIG. 12 shows a graph plotting angle of attack for various types of golf clubs.

FIG. 13 shows a cross-section view of the golf club head of FIG. 9 taken along the line XIII-XIII in FIG. 10.

FIG. 14 shows another cross-section view of the golf club head of FIG. 9 taken along the line XIV-XIV in FIG. 11.

FIG. 15 shows another bottom plan view of the golf club head of FIG. 9.

DETAILED DESCRIPTION OF EMBODIMENTS

Shown in FIG. 1 is a golf club head 100 according to one or more aspects of the present disclosure. The club head 100 may be a hollow-type club head. For example, as shown in FIG. 1, it may be a hybrid or utility-type club head. The club head 100 may generally be formed from metallic and/or nonmetallic materials, such as any one or a combination of aluminum, stainless steel, titanium, composites, polymeric materials, and any other suitable material.

The club head 100 may include a front portion 110, which has a striking wall including a striking face 112 for contacting a golf ball, and a rear portion 120. The striking face 112 may include a face center 114, which is the point on the striking face 112 that is equidistant from the striking face periphery in both the horizontal direction and in the vertical direction, as set out in the United States Golf Association's Procedure for Measuring the Flexibility of a Golf Club Head (Revision 2.0, Mar. 25, 2005), in which "face center" is described as identifiable using a designated template for such purpose. The club head 100 may further include a toe portion 130, a heel portion 140, a sole portion 150, and a top portion, or crown, 160. The heel portion 140 may include a hosel 142 configured to receive and secure a shaft (not shown) of the golf club. And the club head 100 may include a club head center of gravity at the location 170.

The top portion 160 of the club head 100 may include a raised peripheral portion 162, which may provide additional structural integrity to the club head. This portion 162 may also increase, especially relative to prior club heads, the club head 100's moment of inertia ("MOI") about a vertical axis passing through the center of gravity 170, i.e., I_{zz} . The top portion 160 may also include a step-down 164 that further lowers the center of gravity 170 and thus locates the sweet spot, which is a normal projection of the center of gravity 170 on the striking face 112, in a location more proximate the intended, e.g., average, impact point of the golf ball and the golf club head 100. A weight pad (not shown) may also be located on the interior of the sole portion 150 to yet further increase the MOI and reduce the height of the center of gravity for similar purposes. And being a utility-type club head, the loft angle, i.e., the angle formed between a virtual vertical hosel plane containing an axis of the hosel 142 and a striking face plane substantially parallel to the striking face 112, of the club head 100 may preferably be no greater than 26° . More preferably, this loft angle may be between 14° and 26° , and even more preferably between 18° and 24° . In embodiments where the striking face includes a bulge and/or roll, the virtual striking face plane may be considered to be a plane tangent to the face center of the striking face.

As perhaps best shown in FIGS. 2 and 3, the sole portion 150 of the club head 100 may include a plurality of rails 200

that are each preferably elongate in the front-to-rear direction. More specifically, the club head 100 may include a central sole rail 210 laterally centered in the heel-to-toe direction with the face center 114, a toe-side sole rail 220, and a heel-side sole rail 230. A recess 240 in the sole portion 150 may space the central 210 and toe-side sole portions 220 from each other, and a recess 250 in the sole portion 150 may space the central 210 and heel-side sole portions 230 from each other. Each recess 240, 250 may include a bottom surface at least partially circumscribed by a side surface. The recesses 240 and 250 between the guide rails 210, 220, and 230 may channel debris therethrough during a swing, thereby reducing interaction and friction between the club head 100 and the turf and leading to improved speed retention. They may also cause the golfer to perceive the volume of the rails 210, 220, and 230 to be greater, thereby potentially increasing the golfer's confidence in the club head 100 and the shots to be made by it.

FIG. 4 shows a cross-section of the golf club head 100 taken along a virtual vertical plane IV that intersects the face center 114 and thus the central sole rail 210. As shown in this Figure, the sole portion 150 may include a leading edge 152 and a trailing edge 154, which respectively represent the forward-most and rearward-most extents of the sole portion 150. FIG. 4 shows the golf club head 100 in the reference position, which as used herein, refers to an orientation of a club head, e.g., the club head 100, relative to a virtual ground plane 300, in which the club head 100 is permitted to rest on the ground plane such that the sole portion 150 of the club head 100 contacts the ground plane at a sole contact point 158 between the edges 152 and 154, and a hosel axis of the hosel 142 is oriented such that the club head 100 is at its designated loft angle relative to the virtual ground plane 300 and the hosel axis lies at the club head's designated lie angle.

The edges 152 and 154 may define therebetween a sole length 156, which may otherwise be indicated by "Ls." The sole length 156 may preferably be no less than 35 mm, more preferably no less than 45 mm, and even more preferably, it may be between 45 mm and 65 mm. The setback length 180 of the sole contact point 158 from the leading edge 152 in the front-to-rear direction, otherwise referred to as "D1," may also be defined. For example, the setback length 180 may preferably be no greater than 0.8^*Ls , more preferably no greater than 0.5^*Ls , and even more preferably no greater than 0.25^*Ls . In terms of absolute value, the setback length 180 may be between 5 mm and 15 mm and even more preferably between 8 mm and 12 mm. And as also shown in FIG. 4, the leading edge 152 may also define a height 182, or "H1," and a bounce angle 184. The height 182, which is the distance between the leading edge 152 and the virtual ground plane 300, may preferably be no less than 5 mm, more preferably no less than 6 mm, and even more preferably no less than 7 mm. And the bounce angle, which is the angle between the ground plane 300 and a virtual line 55 extending through the leading edge 152 and the sole contact point 158 may be between 2° and 18° degrees, preferably between 10° and 18° .

FIG. 5 shows yet further detail of the radius of curvature of the sole portion 150 along the virtual vertical plane IV. The radius of curvature of the sole portion 150 changes in the front-to-rear direction of the club head. The "blend" of the various radii of curvature has perhaps the largest impact on the sole's ability to minimize speed loss due to turf interaction. At a forward location no more than 3 mm from the leading edge 152, the radius of curvature 190 of the sole portion 150, or "R1," may preferably be no greater than 30 mm, more preferably no greater than 20 mm, and even more

preferably no greater than 16 mm. Most preferably, the radius of curvature **190** of the sole portion **150** may be between 10 mm and 16 mm. At a more rearward location that is spaced no less than 3 mm rearward of the leading edge, the radius of curvature **192** of the sole portion **150**, or "R2," may preferably be no less than 100 mm, more preferably no less than 200 mm, and even more preferably no less than 250 mm. Preferably, the radius of curvature **192** is greater than ten times the radius of curvature **190**, more preferably is greater than 15 times the radius of curvature **190**, and most preferably is between 18 and 25 times the radius of curvature **190**. Preferably, the radius of curvature of the sole portion **150** may decrease rearward relative to the radius of curvature **192** toward an intermediate minimum radius of curvature **194**, or "R3" or "Rmin," at a point near the sole contact point **158** and closer to the leading edge **152** than the trailing edge **154**. In some embodiments, R3 corresponds with the sole contact point of the sole portion. The radius of curvature of the sole portion **150** may then increase toward the trailing edge **154** to a maximum radius of curvature **196**, or "R4," and it may thereafter decrease to a radius of curvature **198**, or "R5," near the trailing edge **154**. The radius of curvature of the sole portion **150** may thus vary in a central region of the sole portion **150** delimited by a forward end spaced 3 mm rearward of the leading edge **152** and a rearward end spaced 3 mm forward of the trailing edge **154** such that radius of curvature **194** < radius of curvature **192** < radius of curvature **196**.

Returning to FIG. 3, the widths **212**, **222**, and **232** of the central sole rail **210**, toe-side sole rail **220**, and heel-side sole rail **230** in the heel-to-toe direction may preferably vary in the front-to-rear direction. The width **212** of the central sole rail **210** in particular may preferably taper in the forward direction. It may preferably taper toward a minimum at a location **214** between the leading **152** and trailing **154** edges of the sole portion **150** so that its maximum width is at a location **216** at the rear of the sole portion. This location **214** of minimum width may preferably be located closer to the leading edge **152** of the sole portion **150** than to the trailing edge **154**. More specifically, its distance **218** may preferably be between 5 mm and 15 mm from the leading edge **152** and more preferably between 6 mm and 12 mm from the leading edge. This location **214** may also be located less than 50% of the sole length **156** from the leading edge **152** of the sole portion **150**, more preferably between 10% and 25% of the sole length **156** from the leading edge, and even more preferably between 15% and 22% of the sole length **156** from the leading edge. Moreover, the maximum value of the width **212** at the location **216** may preferably be greater than or equal to 7 mm, more preferably greater than or equal to 10 mm, even more preferably between 12 mm and 18 mm, and most preferably equal to or about 15 mm. The minimum value of the width **212** at the location **214** may in turn preferably be between 5 mm and 12 mm, more preferably between 7 mm and 10 mm, and most preferably equal to or about 9 mm.

FIG. 6 shows another cross-section of the golf club head **100** taken at the virtual vertical plane VI shown in FIG. 1. As shown in this Figure, each of the sole rails **210**, **220**, and **230** may be elevated relative to the adjacent portions of the sole portion **150**. For example, the portion of the central sole rail **210** closest to the virtual ground plane **300** when in the reference position may extend from the surfaces of the adjacent recesses **240** and **250** by an elevation **218**. This elevation **218** may preferably be no less than 3 mm. It may more preferably be between 3 mm and 6 mm. And it may even more preferably be equal to or about 4 mm. This

elevation **218** may be created by way of stepped-down portions **260** and **270** (FIG. 3) at the front of the sole portion **150**. These stepped-down portions **260** and **270** lead to the recesses **240** and **250**, respectively, and they are thus responsible for increasing the clearance and perceived depth of the sole rails **210**, **220**, and **230**. The vertical depth of the stepped-down portions **260** and **270** relative to the front of the sole portion **150** is preferably greater than or equal to 2 mm and more preferably greater than or equal to 3 mm.

FIG. 7 shows a comparison of the club head speed at impact for an exemplary golf club head in accordance with the present disclosure, e.g., the golf club head **100**, and a prior comparative club head, which lacks the sole rails **200**. As can be seen, although the head speed is initially the same for the two club heads, interaction with the turf beginning at about 0.002 seconds reduces the speed of the comparative club head substantially more than that of the exemplary club head. FIGS. 8A and 8B in turn show the turf dispersion at impact with the golf ball between the comparative club head and the exemplary club head, respectively. The comparative club head disperses more turf and creates a larger wake along the areas near the toe and heel of the club head than the exemplary club head. The exemplary club head according to the present disclosure thus improves speed retention, leading to a more consistent and predictable distance and trajectory on struck shots.

Shown in FIGS. 9-15 is another golf club head **400**. The club head **400** may be a hollow-type club head. For example, it may be a club head for a fairway wood. The club head **100** may generally be formed from metallic and/or nonmetallic materials, such as any one or a combination of aluminum, stainless steel, titanium, titanium alloys, composites, polymeric materials, and any other suitable material.

Like the golf club head **100**, the club head **400** may include a front portion **410**, which has a striking wall including a striking face **412** for contacting a golf ball, and a rear portion **420**. The striking face **412** may include a face center **414**, which like the face center **114** is the point on the striking face **412** that is equidistant from the striking face periphery in both the horizontal direction and in the vertical direction, as set out in the United States Golf Association's Procedure for Measuring the Flexibility of a Golf Club Head (Revision 2.0, Mar. 25, 2005), in which "face center" is described as identifiable using a designated template for such purpose. A virtual vertical center plane **416**, which extends in the front-to-rear direction, may intersect the face center **414**. The club head **400** may further include a toe portion **430**, a heel portion **440**, a sole portion **450**, and a top portion, or crown, **460**. The heel portion **440** may include a hosel **442** configured to receive and secure a shaft (not shown) of the golf club. And the club head **400** may include a club head center of gravity at the location **470**.

As best shown in FIG. 10, the top portion **460** of the club head **400** may also include a raised forward portion **462**, which may provide a higher topline and larger surface area of the striking face **412**. This portion **462** may also increase, especially relative to prior club heads, the club head **400**'s moment of inertia ("MOI") about a vertical axis passing through the center of gravity **470**, i.e., I_{zz} , and the club head **400**'s MOI about a horizontal axis passing in a heel-to-toe direction through the center of gravity **470**, i.e., I_{xx} . The top portion **460** may also include a step-down **464** that further lowers the center of gravity **470** and thus locates the sweet spot **472**, which is a normal projection of the center of gravity **470** on the striking face **412**, in a location more proximate the intended, e.g., average, impact point of the golf ball and the golf club head **400**. The center of gravity

depth, i.e., the distance between the sweet spot on the striking face 412 and the center of gravity 470 along that normal projection, may be a distance 474 of at least 25 mm, and more preferably at least 31 mm. And the loft angle, i.e., the angle formed between a virtual vertical hosel plane containing an axis of the hosel 442 and a striking face plane substantially parallel to the striking face 412, of the club head 400 may preferably be at least 13°. More preferably, this loft angle may be between 13° and 21°. In embodiments where the striking face includes a bulge and/or roll, the virtual striking face plane may be considered to be a plane tangent to the face center of the striking face.

As perhaps best shown in FIGS. 9 and 11, the sole portion 450 of the club head 400, like that of the club head 100, may include a plurality of rails 500 that are each preferably elongate in the front-to-rear direction. More specifically, the club head 400 may include a toe-side sole rail 510 and a heel-side sole rail 520. As shown in FIG. 15, surface portions of these rails 510 and 520 may constitute a plurality of, e.g., 2, ground contact regions 511 and 521. These ground contact regions 511 and 521 may be elongate in shape when the club head is allowed to naturally settle to a rest position, which is approximately the same head orientation as the reference position, and they may be spaced apart in the heel-to-toe direction by about 40 mm. By having separate ground contact regions, the club head 400 may be less prone to wobble at address and may have greater face angle stability, i.e., it may be less likely to flop open with changing lie angle than a golf club head with, e.g., just one ground contact region. Returning to FIG. 11, a width 530 in the heel-to-toe direction of the rail 510, and preferably also of the rail 520, may be greater than 7 mm, more preferably greater than 9 mm. A depth or length 540 in the front-to-rear direction of the rail 510 may in turn be greater than 85 mm, and more preferably greater than 90 mm. The length 540 may also preferably be less than 115 mm. As shown in FIG. 11, the rail 510 may preferably have a front-to-rear length 540 that is a substantial proportion of the front-to-rear depth of the golf club head 456 from its forwardmost point to its rearwardmost point. For example, the length 540 of the toe-side rail may be greater than 90% of the length 456, and more preferably the length 540 may be greater than 95% of the length 456. The length 540 may also differ from a depth or length 550 of the heel-side sole rail 520 in the front-to-rear direction. For example, the length 550 may be at least 10 mm less than the length 540.

As shown in FIG. 12, golfers generally apply a very shallow angle of attack when swinging a fairway wood, as opposed to “swinging down” on the ball with a steep angle of attack when swinging shorter clubs such as irons. Rails that span a substantial length on longer fairway woods help to improve turf interaction by increasing the length of time the rails contact the ground and stabilize the club head through impact. Additionally, the dimensions and geometry of the rail design shown in FIGS. 9 and 11 can help to correct and compensate for a steep angle of attack, which can often result in “chunked” shots.

Returning to FIG. 9, the club head 400 is shown in the reference position relative to a virtual ground plane 600. A height 560 of the rails 510, 520 from the adjoining sole portion 450 to the ground plane 600 may preferably be no more than 2.5 mm, and more preferably no more than 2.0 mm. Each of the rails may include a pair of side walls 513 or 523 that extend downward to a base surface 515 or 525. The lowermost, base surface of each of the rails may be angled relative to the ground plane 600 at an offset angle 502 of 7° to 10°. The rails, e.g., the rail 510, may be spaced

entirely in the heel-to-toe direction from the virtual vertical center plane 416 by a distance 570 of at least 15 mm, and more preferably by a distance 570 of at least 20 mm. As used herein “spaced entirely” means that no portion of, e.g., the rail 510, is closer to the virtual vertical center plane 416 than the distance 570. The aforementioned height, spacing, and front-to-rear orientation of the rails 500 may beneficially lower the center of gravity 470, improve stability at address (to ensure proper face angle), and allow for the appearance of a low profile at address. And at the reference position shown in FIG. 9, and as discussed previously in connection with FIG. 15, the club head may only contact the ground plane 600 at one or both of the rails 510, 520. Thus, the sole portion 450 may be spaced from the virtual ground plane 600 at the virtual vertical center plane 416.

The design of the rails 500 may allow for discretionary mass to be selectively located in beneficial regions of the sole portion. For example, as shown in FIG. 13, and as with the club head 100, a weight pad 580, which may be a thickened part of the sole portion 450, may be located on the interior of the sole portion 450 to yet further increase MOI and reduce the height of the center of gravity. For example, a height of the center of gravity above the ground plane 600 may be no greater than 16 mm. Preferably, the sole rails and weight pad 580 may be integrally formed by casting to reduce manufacturing and material costs. The weight pad 580 may span the interior of the sole portion 450 from the heel portion 440 to the toe portion 430, and it may be situated forward of an internal rib 582, which may traverse the inner side of the sole rails 500 to improve acoustic properties of the club head. As perhaps best shown in FIG. 14, which shows a cross-section through the center of the rail 520, a central region 522 of that rail may be filled as part of the weight pad 580. On the other hand, a region 524 of the rail 520 proximate to the striking face 412 may in turn be left hollow to increase the depth of the center of gravity. A rearward region 526 of the rail 520 may likewise be left hollow. Preferably, the toe-side sole rail 510 may be similarly formed, with a filled central region 512 and hollow regions 514 and 516.

The effectiveness of the golf club head 400, and particularly that of the rails 500, is made apparent by way of Table 1 below. “Oval Offline” and “Oval Area” are measures of shot consistency, in which standard deviation values for offline distance (left or right) and carry distance are calculated and used to create major and minor axes of an ellipse (axes are 2*std deviation in length). The player data shown in Table 1 below indicate both increased ball speed and distance and improved shot consistency with the exemplary club head, i.e., a golf club head such as the club head 400.

TABLE 1

	Oval Offline (yds)	Oval Area (yds ²)	Ball Speed (mph)	Carry Distance (yds)	Flight Distance (yds)
Exemplary Club Head	17.9	335	133.5	187.5	199.4
Comparable Club Head w/o Rails	27.9	474	132.1	185.3	196.3

In the foregoing discussion, the present invention has been described with reference to specific exemplary aspects thereof. However, it will be evident that various modifications and changes may be made to these exemplary aspects without departing from the broader spirit and scope of the invention. Accordingly, the foregoing discussion and the

accompanying drawings are to be regarded as merely illustrative of the present invention rather than as limiting its scope in any manner.

What is claimed is:

1. A wood-type golf club head that, when oriented in a reference position relative to a virtual ground plane, comprises:

- a loft greater than 13 degrees;
- a depth in a front to rear direction no less than 75 mm;
- a striking face including a face center located in a virtual vertical center plane that extends in the front to rear direction;
- a rear portion opposite the striking face;
- a heel portion;
- a toe portion opposite the heel portion;
- a crown; and
- a sole opposite the crown, the sole including:
- a first rail that has a length in the front to rear direction that is at least 90% of the front to rear depth of the club head and is entirely spaced in a heel to toe direction more than 15 mm from the virtual vertical center plane; and
- a second rail that extends substantially parallel to the first rail and is entirely spaced in the heel to toe direction more than 15 mm from the virtual vertical center plane,

wherein,

- the first rail and the second rail are spaced the same distance in the heel to toe direction from the virtual vertical center plane,
- the first rail and the second rail are each at least 7 mm in width,
- the second rail is heel-ward of the virtual vertical center plane and a second rail length is at least 10 mm less than the first rail length,
- the first and second rails each have a rail height no more than 2 mm,
- within the virtual vertical center plane, the golf club head is entirely spaced from the virtual ground plane, the first rail contacts the virtual ground plane.

2. The golf club head of claim 1, further comprising an internal weight structure that partially fills at least one of the first and second rails.

3. The golf club head of claim 2, wherein the first and second rails are both partially hollow.

4. The golf club head of claim 2, wherein the internal weight structure is integrally formed with the sole and at least one of the first and second rails.

5. The golf club head of claim 1, wherein each of the first and second rails is entirely spaced in the heel to toe direction at least 20 mm from the virtual vertical center plane.

6. The golf club head of claim 1, wherein the first rail is toe-ward of the virtual vertical center plane and the first rail length is at least 80 mm.

7. The golf club head of claim 1, where the first rail includes a pair of side walls that extend downwardly to a first rail base surface with a first offset angle of between seven degrees and 10 degrees.

8. The golf club head of claim 1, wherein the first rail length is at least 95% of the club head's front to rear depth.

9. The golf club head of claim 1, wherein the crown includes a forward portion and a stepped down portion rearward of the forward portion.

10. The golf club head of claim 1, further comprising a center of gravity depth from the striking face of at least 31 mm.

11. The golf club head of claim 1, wherein the front to rear depth of the club head is no less than 90 mm.

12. A wood-type golf club head that, when oriented in a reference position relative to a virtual ground plane, comprises:

- a loft greater than 13 degrees;
- a striking face including a face center located in a virtual vertical center plane that extends in a front to rear direction;
- a rear portion opposite the striking face;
- a heel portion;
- a toe portion opposite the heel portion;
- a depth in the front to rear direction;
- a width in a toe to heel direction that is at least 80% of the depth;
- a crown; and
- a sole opposite the crown, the sole including:
- a first rail that has a length in the front to rear direction no less than 80 mm and is entirely spaced in the heel to toe direction more than 15 mm from the virtual vertical center plane; and
- a second rail that extends substantially parallel to the first rail and is entirely spaced in the heel to toe direction more than 15 mm from the virtual vertical center plane,

wherein,

- the first rail and the second rail are each at least 7 mm in width,
- the second rail is heel-ward of the virtual vertical center plane and a second rail length is at least 10 mm less than the first rail length,
- the first rail and the second rail are spaced the same distance in the heel to toe direction from the virtual vertical center plane,
- the first and second rails each have a rail height no more than 2 mm,
- within the virtual vertical center plane, the golf club head is entirely spaced from the virtual ground plane, and
- the first rail contacts the virtual ground plane.

13. The golf club head of claim 12, further comprising an internal weight structure that partially fills at least one of the first and second rails.

14. The golf club head of claim 13, wherein the first and second rails are both partially hollow.

15. The golf club head of claim 13, wherein the internal weight structure is integrally formed with the first and second rails and the sole.

16. The golf club head of claim 12, wherein the crown includes a forward portion and a stepped down portion rearward of the forward portion.

17. The golf club head of claim 13, wherein the crown, the sole, and the internal weight structure comprise a unitary investment casted component and wherein the golf club head includes a center of gravity having a center of gravity height no greater than 16 mm.
